AQUARIUM

Charles D. Kuneff, 891 Cedar St.,
Alameda, Calif. 94501

Filed Dec. 4, 1972, Ser. No. 312,230

Term of patent 14 years

Int. Cl. D30—02

U.S. Cl. D30—9

Fig. 2

Fig. 4

Fig. 3

FIG. 1 is a side elevational view of an aquarium showing my new design;

FIG. 2 is a top plan view thereof;

FIG. 3 is a bottom plan view thereof; and

FIG. 4 is a right-end elevational view, the opposite end being a mirror image thereof.

I claim:

The ornamental design for an aquarium, as shown and described.
